UNITED STATES PATENT OFFICE.

HARVEY M. WOOD, OF DENVER, COLORADO.

PLANE.

SPECIFICATION forming part of Letters Patent No. 758,948, dated May 3, 1904.

Application filed October 2, 1902. Serial No. 125,684. (No model.)

To all whom it may concern:

Be it known that I, HARVEY M. WOOD, a citizen of the United States, residing at Denver, in the county of Arapahoe and State of Colorado, have invented a certain new and useful Improvement in Planes, of which the following is a specification.

My invention relates particularly to a device for automatically raising the plane slightly above the surface of the wood when the plane is being drawn back.

One object of my invention is to provide a device whereby the cutting edge of the plane-iron will be prevented from dulling by coming in contact with the wood during the backward movement of the plane.

Another object of my invention is to provide a device of the character described which may be thrown into or out of operation, as desired.

Another object is to produce a device of the character described in which the backward movement of the plane will be free and even and not partake of the vibration caused by the device rattling over the saw-kerf.

Other objects are to provide a device of the character described which is simple in construction, effective in operation, and which may be adapted to be placed upon various types of planes.

Referring to the drawings, Figure I is a side elevation of a plane equipped with my device, a portion of the device being shown in section. Fig. II is a section taken through the device on the line II-II of Fig. III, also showing part of the plane-stock. Fig. III is a sectional view of the device, showing the parts in one position. Fig. IV is a sectional view of the device, showing the parts in another position. Fig. V is a sectional view through the device, showing the parts in still another position. Fig. VI is a perspective of the shoe. Fig. VII is a perspective of the stop, also showing part of a locking device. Fig. VIII is a detail, partly in section, of a portion of the locking device.

The invention includes a shoe which is rotatably mounted, preferably at the front of the plane, and which is provided with a cam-face adapted to contact with the surface of the

wood or other material being planed for tilting the plane during the back stroke and raising the knife from the wood.

The invention also includes means for throwing the device into or out of operation and means for locking the device in either operative or inoperative position.

1 designates a shoe which is provided with a pair of oppositely-arranged lugs 2 on each side thereof. The lugs 2 are perforated, as at 3.

4 designates a flat face which lies at an angle to the plane of the main portion of the shoe. The shoe is rotatably mounted on a pin 6, which passes through the perforations 3 in 65 the lugs 2. The pin is carried by the opposite wings of the stock. The stop 5 is provided with opposite wings 6^a, which are perforated, as at 7.

8 is a circular hood which may be attached 70 to the stock of the plane by means of lugs 9 and screws 10. The pin 6 projects through the perforations 7 of the wings 6^a. The shoe 1 and stop 5 are supported by pin 6, which latter may preferably be in the form of a screw 75 with a slotted head 11, as shown in Fig. II.

The wings of the stop 5 are triangular in outline, one side of the triangle being curved to conform to the contour of the hood 8 and being concentric therewith.

80

The shoe 1 is provided with a helical cam-face 12, which is gradually curved away from the flat portion of the shoe 1. The straight flat portion of the shoe is tangent to the curved cam-face 12, the point of departure 85 being slightly to the right of a line *a* drawn perpendicular to the flat face of the shoe and passing through the pivotal point when the shoe lies as in Fig. V.

The stop 5 may be rocked upon the pin 6 90 into two positions, one position it takes being shown in Fig. III and the other position it may have being shown in Fig. IV. When the stop 5 is in the position shown in Fig. III, the shoe is prevented from projecting below 95 the bottom surface of the plane.

When the carrier is in the position shown in Fig. V and the plane is moved to and fro, the shoe is oscillated by reason of its cam-face contacting and bearing upon the surface 100

of the wood being planed. When the plane is being moved backward, the friction between the cam-face 12 of the shoe and the upper surface of the wood rocks the shoe in the direction indicated by the arrow, which causes the face 4 to strike against the wall of the stop 5. In this position the flat portion of the shoe makes a sliding contact with the upper surface of the wood being planed, the plane being thereby tilted and the knife raised above the surface of the wood.

When the plane is moved ahead, friction between the wood and cam-face 12 oscillates the shoe the opposite direction and throws the shoe into approximately the position shown in Fig. IV, in which position it has been rocked to a degree sufficient to bring the flat bearing part of the shoe away from the upper surface of the wood, leaving the retreating part of the cam-face 12 flush with the lower face of the plane and slightly contacting with the wood, and allowing the plane to rest flat upon the surface of the wood.

When the plane is drawn back, the friction between the cam-face 12 and the upper surface of the wood causes the shoe to be rocked again into the position shown in Fig. V.

The longitudinal movement of the plane required to effect the oscillation of the shoe sufficiently to bring it into or out of position is very slight, so that the shoe takes its position almost immediately at the change of each stroke of the plane.

Referring to Fig. V, it will be seen that with the shoe in its lower position the point of tangency between the straight portion of the shoe and the curved cam-face 12 is slightly to the right of a vertical line drawn through the pin 6, so that the weight of the plane will not result in an upward tilting of the shoe, which might possibly occur if the point of tangency occurred directly under or to the left of the center.

The movable shoe 1, carried by the plane-stock, is adapted in its operative position (shown in Figs. IV and V) to operate by contact with the surface to be planed to lift the plane on its back movement, and the movable stop 5 is adapted in one position to appropriately stop the shoe and in another position to extend below the shoe to inclose the same in the stock. The pin 13 is adapted to engage the stock to lock the stop in one and the other of these positions at the pleasure of the operator.

I do not propose to limit the device by any specific form of the elements shown.

The action of the shoe is entirely automatic, the friction between the shoe and wood caused by moving the plane being the force which oscillates the shoe. Hence the action of the device is not dependent upon gravity or springs.

In order to hold the stop 5 locked in either of its two positions, I have provided a pair of shouldered pins 13. (See Figs. II and VIII.)

Each pin projects through and somewhat beyond a perforation in each wing 6^a of the stop. A coiled spring 14 lies between the inner ends of the pins 13 and within a tube 14^a and serves to press the pins outward, so that their shoulders rest against the inside faces of the wings 6^a.

Each wing of the stock is provided with a perforation, as at 15 and 16. The perforations 15 and 16 lie within the arcs which are described by the pins 13 when the stop is rocked. When the stop is rocked into the position shown in Fig. IV, a pin 13 enters the perforation 15, thus locking the stop in that position. When the stop is moved into the position shown in Fig. III, the opposite pin 13 moves into the perforation 16 on the opposite side of the hood.

In order to unlock the stop before changing its position, any convenient article, such as a nail, may be pressed against the end of whichever pin projects through the hole, and the pin thereby pushed in, which unlocks the carrier, after which the carrier may then be rocked to the position desired, when the opposite pin will automatically enter the opposite perforation in the hood.

The device is preferably attached to the front end of the plane, the bottom of the stock being cut away and having an opening the length of which is equal to the length of the opening in the bottom of the hood to allow the shoe to protrude and also to allow the lower end of the stop to sweep around when the stop is moved from one position to the other.

During the cutting stroke of the plane the stock of the plane rests flat upon the wood, the shoe being rolled out of the way. When the plane is drawn back, the front end of the plane is slightly raised, the stock of the plane tilted, and the knife or plane-iron thereby raised slightly above the surface of the wood, so that dulling of the knife is prevented.

If it is desired to throw the device out of operation, the stop may be moved to the position shown in Fig. III and locked. The plane then operates in the ordinary way, the knife scraping along the wood, as usual.

The flat surface of the shoe is of such size that it does not enter the saw-kerf and cause the plane to rattle, but glides easily over the ridges or rough undressed surface of the wood being planed.

It should be understood that I do not limit myself to the specific construction herein shown and described, as it is evident that many changes may be made in the particular construction shown and described without departing from the spirit of my invention.

When the plane is lifted away from the work, the shoe drops by gravity into the position shown in Fig. V, so that in laying down the plane upon the bench the shoe holds the front end of the plane up and keeps the knife off the bench.

By the term "bearing-face" I mean a wearing face or surface adapted to rest upon and slide along the surface of the material being planed.

5 Now, having described my invention, what I claim, and desire to secure by Letters Patent of the United States, is—

1. In a plane, in combination with the stock thereof, a shoe rotatably pivoted to the stock 10 and having a face which projects below the stock, and having another face which merges with the first face and veers away from the bottom of the stock whereby the friction between the shoe and the face of the wood being planed rocks the shoe and causes the two faces to be alternately brought into contact with the wood, thereby raising the plane during the back stroke.

2. In a plane, in combination with the stock 20 thereof, a shoe rotatably mounted on the stock, said shoe having a flat bearing-face, and a curved bearing-face the distance from the pivotal point of the shoe to the flat bearing-face of the shoe being greater than the 25 distance from said pivotal point to the bottom of the stock.

3. In a plane, in combination with the stock thereof, a shoe rotatably connected to said stock, said shoe having a flat bearing-face 30 and a curved bearing-face the distance from the pivotal point of the shoe to the flat bearing-face of the shoe being greater than the distance from said pivotal point to the bottom of the stock, and adjustable means for 35 limiting the movement of the shoe.

4. A plane-stock, a shoe rotatably mounted on the stock and adapted to project below the stock, when in one position and adapted to not so project when in another position and 40 a pivot-stop adapted in one position to stop the shoe when it projects to lift the stock, and in another position to extend below the shoe.

5. In a plane, in combination with a stock 45 thereof, a stop pivotally connected to the stock and a shoe rotatably mounted on said stock, said shoe having a helical bearing-face and a flat bearing-face tangential to said helical face, said flat bearing-face being movable 50 below the bottom of the stock.

6. A plane-stock, a shoe rotatably mounted on the stock and adapted to project below the stock when in one position and adapted to not so project when in another position, a stop 55 adapted in one position to stop the shoe, and means for locking the stop in such position.

7. A plane-stock, a shoe movably mounted on the stock and adapted to project below the stock when in one position and adapted to not

so project when in another position, a movable 60 stop for said shoe, and means for locking the stop in different positions.

8. In a plane, in combination with the stock thereof, a stop pivoted to said stock, and comprising a lateral wall and opposite wings, a 65 shoe pivoted to the stock and lying between said wings, said shoe having a plane bearing-face and a curved bearing-face, the plane bearing-face of the shoe projecting below the bottom of the stock and a hood mounted on 70 the stock and inclosing said shoe and stop.

9. A plane-stock, a shoe pivoted thereon and adapted to be moved into and out of operative condition, a movable stop for limiting the swing of the shoe when in operative condition, a pin for locking the stop to the stock, and means for forcing the pin into locking position, the shoe when in operative condition adapted to project below the stop when in one position and adapted to not so project 80 when in another position.

10. In a plane, in combination with the stock thereof, a stop pivoted to the stock, a shoe pivoted to the stock and projecting below the same, a spring-pressed pin slidably connected 85 with the stop, said stock having a perforation for receiving said pin, a hood mounted on the stock and inclosing said shoe and stop.

11. In a plane, in combination with the stock thereof, a stop pivoted to the stock a shoe pivoted to the stock and projecting below the same, and comprising a wall with opposite perforated wings, locking-pins projecting through each wing, a spring between said locking-pins, a tube between the wings inclosing the locking-pins and spring, said stock having a perforation in each side thereof to receive the locking-pins.

12. In a plane, in combination with the stock thereof, a stop pivoted to the stock, a shoe pivoted to the stock and projecting below the same, and a single pin passing through the stock, stop, and shoe.

13. In a plane, in combination with the stock thereof, a stop pivoted to the stock, a shoe pivoted to the stock and projecting below the same, and a single pin passing through the stock, stop and shoe, and means for locking said stop in different positions.

In testimony whereof I have signed my name 110 to this specification, in the presence of two subscribing witnesses, at Los Angeles, in the county of Los Angeles and State of California, this 26th day of September, 1902.

H. M. WOOD.
